INDUCTANCE COIL FITTED WITH IRON
DUST COREHugh Charles Hebard, Greenford, England, as-
signor to Johnson Laboratories Incorporated,
Chicago, Ill.Application October 5, 1938, Serial No. 233,465
In Great Britain October 6, 1937

2 Claims. (Cl. 74—57)

This invention relates to inductance coils fitted with "dust" cores, i. e. cores composed of a mass of magnetic particles electrically insulated from one another and serving to increase the inductance of the coils at high frequencies. Such coils are used as radiofrequency tuning coils for wireless receivers and for other purposes.

In order to enable the inductance of such coils to be set accurately for the purpose of tuning a number of circuits to the same frequency it is convenient to provide for adjustment of the core relatively to the coil, but when two coils are electromagnetically coupled together such adjustment of the core usually alters the coupling to an undesirable extent. Serious difficulty then arises by reason of the impossibility of altering the self inductance of one coil without disturbing the coupling between the coils.

According to the present invention, in order to overcome this difficulty in a simple manner, the core is divided into two parts one of which is placed in a region where the flux linking with both coils is relatively strong whilst the other is placed in a region where the flux links mainly with one coil only so that by adjustment of the last mentioned part of the core the self inductance of the last mentioned coil can be varied with but slight effect upon the mutual inductance of the two coils.

According to another aspect of the invention, variation of the inductance of one coil is effected by means of a variable air gap located in a region where the flux linking with one coil is strong as compared with the flux linking with both coils.

The invention also provides an improved device for adjusting the core relatively to the coil, comprising a fixed sleeve formed with a helical cam surface at each end, a rod or bar rotatable and axially slideable in the sleeve and two projections fixed to the rod or bar, each of the projections being located against one of the helical cam surfaces so that rotation of the rod or bar causes the same to be displaced axially either forwards or backwards according to the direction of rotation.

The invention will be more readily understood from the following particular description with reference to the accompanying drawing in which:

Figure 1 is a sectional view of an inductance device constructed according to one form of the invention,

Figure 2 is a similar view showing a modified construction embodying the improved adjusting device hereinbefore referred to, and

Figures 3 and 4 are detail views showing the construction of the sleeve formed with the helical cam surfaces.

The inductance coil shown in Figures 1 and 2 of the drawing comprises a multi-layer solenoidal coil divided into sections in such a manner as to reduce the self-capacity of the coil. The coil 1 is mounted on a former 2 and a coupling coil 3 is mounted adjacent the coil 1 as shown.

The device is fitted with a dust core in the form of a rod or bar divided into two parts 4 and 5. The part 5 extends from a point intermediate the ends of the coil 1 up to and through the coupling coil 3. The part 4 is axially adjustable from a maximum inductance position in which it may be in contact with the part 5 to positions in which the self-inductance of the coil 1 is reduced by reason of the air gap formed between the two parts of the core. It will be obvious that considerable variation of the self inductance of the coil 1 can be obtained by varying this air gap. On the other hand, the mutual inductance between the two coils is due mainly to linkage between the coupling coil 3 and that part of the inductance coil 1 which lies between the coupling coil and the air gap. Consequently, variations of the air gap have comparatively little effect upon the coupling.

The core part 4 consists of a hollow cylinder or tube of magnetic material mounted on a rod 30 or stud 6 by which the core 4 is adjusted and held in adjusted position. In the form of construction shown in Figure 1 of the drawing adjustment is effected by means of a lever arm 7 fixed to the stud 6 and projecting through a helical cam slot 35 8 in the former 2. It will be seen that by rocking the lever 7 so as to rotate the stud 6, a longitudinal movement can be imparted to the core 4 owing to the action of the lever 7 in the slot 8.

Figure 2 of the drawing shows a modified construction in which the stud 6 to which the adjustable core 4 is attached has an extension 9 mounted to slide in a sleeve or hollow plug 10 fixed in one end of the coil former 2. The sleeve or plug 10 is formed at its ends with helical cam surfaces 11 and 12 which co-operate with studs or projections 13 and 14 formed on the part 9. The projecting end of the part 9 is formed with a head 15 constructed so that it can be rotated by means of a screw-driver or other suitable tool.

The stud 6 and its extension 9, together with the projections 13 and 14 and head 15 may consist of a moulding made of vulcanized rubber, synthetic resin or other suitable plastic material and may be formed in one piece.

The sleeve or plug 10 is made of similar material and in order to enable it to be mounted on the part 9 it is constructed in two halves, each of which consists of one half turn of a helicoid. The two parts are held together by means of a ring 16 and they are formed with suitable interengaging projections or recesses 17 as indicated in Figure 3 of the drawing so as to prevent relative displacement of the two halves at the two diametrically opposed joints between them.

When the head 15 is rotated by means of a screw-driver or otherwise, the core part 4 is moved towards or away from the part 5 according to the direction of rotation of the head 15. When the desired adjustment has been made, a quantity of fusible plastic material which will adhere to the material of the head 15 and sleeve 10 may be applied to the head 15 in a molten condition in such a way as to unite the head 15 to the sleeve 10 and prevent relative rotation between them. By this means the device is sealed in adjusted position.

The coil shown in the drawing is intended to be used as a radio frequency coupling coil. The coil 1 is tuned by means of a condenser and the coil 3 forms part of an aperiodic anode or grid circuit which is coupled to the tuned circuit by virtue of the electromagnetic coupling between the coils 1 and 3.

Having thus described my invention, what I claim is:

1. In a high-frequency inductance device having an adjustable ferromagnetic core and including a coil, a device for adjusting the core relatively to the coil comprising a fixed sleeve formed with a helical cam surface at each end, a rod rotatable and axially slideable in said sleeve and having two projections fixed thereto, each of said projections being located against one of said helical cam surfaces so that rotation of the rod causes the same to be moved axially relatively to the coil according to the direction of rotation, said sleeve being composed of two halves each of which has the general form of one-half turn of a helicoid for convenience in assembling said sleeve around said rod.

2. In a high frequency inductance device having an adjustable ferromagnetic core and a co-operating coil, the combination of a fixed sleeve aligned with said core and having similar end cam surfaces, a rod connected with said core and mounted in said sleeve for rotary and axial movements relatively to said sleeve, said rod having projections engaging said cam surfaces, whereby rotating said rod correspondingly moves said core axially of said coil, said sleeve being sectional to facilitate assembly around said rod.

HUGH CHARLES HEBARD. 30
